Patented Apr. 4, 1922.

UNITED STATES PATENT OFFICE.

SAMSON L. TOPLITZ, OF NEW YORK, N. Y.

MOP HOLDER.

1,411,878.

Specification of Letters Patent.

Patented Apr. 4, 1922.

Application filed May 10, 1921. Serial No. 468,229.

To all whom it may concern:

Be it known that I, SAMSON L. TOPLITZ, a citizen of the United States, and resident of the city, county, and State of New York, have invented a certain new and useful Improvement in Mop Holders, of which the following is a specification.

This invention relates to a mop holder for mops and the object of this invention is to 10 provide a simple device of but few parts which will securely and effectively hold the mop in such a manner that all parts of the holder that are liable to mar, will be protected from contact with floors, trim or 15 other parts of the house.

A further object of this invention is to provide a holder which can be used in connection with any of the present forms of mops and which is arranged so that the mop 20 may be readily placed in position and removed from the holder when desired.

A still further object of this invention is to provide a protective cover for the upper portion of the mop, thereby protecting 25 those portions of the mop which are more liable to wear and consequently increasing the life of the mop.

With these objects and other objects which may hereinafter appear in view, I have devised the particular arrangement of parts 30 hereinafter set forth and more particularly pointed out in the claims appended hereto.

Reference is to be had to the accompanying drawing, forming a part hereof in 35 which—

Figure 1 is a perspective view of a mop holder made in accordance with my invention.

Figure 2 is a vertical sectional view of 40 the same.

Figure 3 is a sectional view on the line 3—3 of Figure 2 looking in the direction of the arrows.

Figure 4 is a sectional view on the line 45 4—4 of Figure 2, looking in the direction of the arrows, and

Figure 5 is a sectional view on the line 5—5 of Figure 2, looking in the direction of the arrows.

Throughout the various views of the drawings, similar reference characters designate similar parts.

In the preferred embodiment of my invention as disclosed in the accompanying drawing, the mop is indicated at 1, and consists generally of a number of mop strands 55

which are doubled upon themselves to form a fold 2 at the upper end of the mop. At 3 is shown a reinforcing strip secured about the mop at the fold 2 and which tends to hold the mop together.

A bar 4 is adapted to lie within the fold 2 in the mop and this bar 4 is provided with an enlargement 5 at a central position and from this enlargement 5 is an upwardly extending threaded stud portion 6 which terminates at its upper end in a prong or piercing member 7. The mop handle is shown at 8 and to the end of this mop handle is secured a tubular head 9 which is provided with a square opening 10 in its lower end. At 11 is a nut, the lower portion of which is square so that the same lies within the opening 10 and is thus prevented from turning therein but is removable by removing the handle from the tubular head 9.

The nut 11 is internally threaded to receive the threads 6 on the stud extending from the enlarged portion 10 of the bar 4. The nut is preferably of brass or other non-corrosive material and is thus unaffected by moisture which would readily rust the threaded portions and prevent a ready separation of the parts when desired.

At 12 is shown a protective covering which is preferably made in the nature of a channel shaped section of spring metal provided with a pair of spring jaws 13 which normally tend to come together to clamp the upper end of the mop securely between them. At the lower end of each of these jaws is secured a strip of rubber 14 or the like forming a squeegee portion for the mop. These squeegee strips 14 are secured in place by rivets 15 or other fastening members.

From the foregoing, the operation of my improved mop holder will be readily understood. As herein set forth, the bar 4 lies between the fold 2 of the mop and the protective cover 12 is provided with a central opening through which the piercing member 7 may pass so that the threaded portion 6 can engage with the threads in the nut 11. It will thus be seen that the bar 4 and the head 9 clamp the mop 1 and the protective covering 12 in place. The piercing prong 7 may be of any suitable shape in cross section, but I have found it desirable to make the same substantially triangular as it can readily be used to pierce the mop 1 so that it may extend therethrough and engage with the handle.

2

By using this prong 7 in such a manner any form of mop may be perforated so that it can be accommodated to the holder herein described.

5 Having described my invention, what I claim is:

- 10 1. An article of the class described comprising a mop holder having a bar, a threaded extension on said bar, a handle, a removable threaded portion on said handle for receiving the threaded portion on the bar and a piercing prong on said bar and extending from the threaded portion thereon.
- 15 2. An article of the class described comprising a mop holder having a bar, a handle, means on the handle for engaging the bar, said bar and handle being adapted to clamp a portion of the mop between them and a piercing member on said bar extending through the mop and projecting into the handle portion.
- 20 3. An article of the class described comprising a mop holder having a bar, a handle portion, co-operating means on said handle

portion and bar adapted to interengage and 25 clamp a portion of the mop between them and a piercing member on said bar adapted to extend through the mop and enter into the handle portion.

4. An article of the class described comprising a bar, a threaded portion thereon, a handle, a head thereon having a central opening, a threaded member held in said opening and adapted to receive the threaded portion on the bar and a piercing prong 35 extending from the threaded portion on the bar.

5. An article of the class described comprising a mop, a bar within the same, a prong extending through said mop, a handle, 40 means on said prong for engaging with the handle, a cover extending over the end of said mop and held between the handle and the bar and a pair of squeegee strips secured to the sides of said cover.

45 Signed at the city, county and State of New York, this 27th day of April, 1921.

SAMSON L. TOPLITZ.
